CENTRIFUGAL PUMP

Paul A. Bancel, Montclair, N. J., assignor to
 Ingersoll-Rand Company, Jersey City, N. J., a
 corporation of New Jersey

Application September 26, 1928
 Serial No. 308,492

1 Claim. (Cl. 103—109)

This invention relates to centrifugal pumps and more particularly to improvements in pumps of the general type disclosed in the patent to James K. McIntyre No. 1,680,057 and filed September 23, 1926, bearing Serial No. 137297.

The invention has for its object, to increase the efficiency of a two stage centrifugal pump in which the suction pressure is extremely low, and toward this end the invention contemplates the interposition of means between the two stages of the pump so that a constant head may be maintained on the first stage impeller.

It has been found in actual practice that when a two stage pump, such as that disclosed in the above mentioned patent is in operation, at low loads the second stage wheel of the pump actually performs the entire work to be done while due to lack of water to be pumped, the first stage wheel of the pump is deprived of its load so that the same merely cavitates and churns the fluid within the casing by virtue of the fact that there is an insufficient head on the wheel. This is extremely disadvantageous if not a dangerous situation, for the wheel wears rapidly when at less than full head and the thrust of the second stage is no longer balanced, there being relatively little thrust developed by the first stage impeller. This situation may be corrected in actual practice by placing an elevated loop between the discharge of the first stage and the inlet of the second stage of a two stage pump.

With these and many other objects in view, which will more readily appear as the nature of invention is better understood, the same consists in the construction, combination and arrangement of parts to be more fully described, illustrated and claimed.

In the accompanying sheet of drawing, the figure represents a hotwell pump as actually connected to the hotwell of a condenser and shows the loop interposed between the two stages of the pump.

The device involves in its general organization a main support 10, upon which there is a casing 45 formed in two parts 11 and 12. The lower part 12, is provided with a base 13 and bearing support 14 for the drive shaft 15. Bearings 16 are provided for the shaft and may be of any suitable description. The upper part 11 is adapted to be attached 50 to the lower part 12 in any suitable manner, and the two parts 11 and 12 form stuffing boxes 17 which, with suitable packing material 18 and glands 19, prevent the escape of liquid from the casing.

55 The pump is of the two stage type, there being

provided a first stage wheel 20 and a second stage or "high pressure" wheel 21, both stage wheels being supported and driven by the single central shaft 15.

The first stage wheel 20, is shown as being provided with a relatively large inlet 22 in order that the velocity set up may be relatively low. Similarly, the outlets 23 from the first stage wheel, are relatively large and the diameter of the wheel is comparatively small, in order that the peripheral, relative and absolute velocities may be kept low in this stage. The pump as shown is designed to bring the discharge pressure of the first stage impeller up to at least atmospheric pressure. Preferably the first stage inlet 22 is connected to a source of low pressure such as the condenser by means of a pipe 86. The details of the connection are omitted to avoid unnecessary complication in the drawing. The second wheel or impeller 21, is provided with a comparatively small inlet 30 and a small discharge opening 31. This second impeller is designed to work with a slight pressure at its inlet.

The casing 12 of the pump is provided with an inlet 40 located between the two impellers 20 and 21. This inlet communicates with a passage 41 leading to the impeller inlet 22. The passage 41 is formed by webs 43 cast integrally with the upper and lower parts 11 and 12 of the casing. These webs also serve as a partition for part of the discharge passage leading to the second stage impeller 21. A partition 50 is shown between the web 43 and the lower portion of casing 12, and this partition serves to prevent the fluid from passing from the discharge outlet 23 of the impeller 20 directly to the inlet 30 of the impeller 21, by causing the fluid to pass through an outlet 52 and through a loop 53 extending vertically, having a fall 54 communicating with an inlet 55 in the discharge passage to the second impeller inlet 30. In other words, this loop is directly interposed between the two stages of the pump for a purpose to be more fully hereinafter set forth.

100 The second stage impeller 21 is surrounded by a passage 60, leading to a discharge opening 61 for connection with a suitable delivery pipe (not shown). The shaft 15 is provided with a suitable flange 63 for connection with a source of power for rotating the impellers 20 and 21.

105 The impellers 20 and 21 are opposed to each other on their faces and the unbalanced areas of the high and low pressure impellers are proportioned so that the thrust on one impeller 110

balances the thrust on the other with the pump operating at normal discharges.

Returning now to the above mentioned loop which is interposed between the two stages, it 5 will be seen that the interposition of this loop presents an efficient means for causing the low pressure impeller to have a full head regardless of the load. The result of this loop interposed between the stages of the pump is that in the 10 first stage the action is similar to a regular hot-well pump and the first stage wheel lifts into what corresponds to a tank or fluid potential. The second stage pumps from the discharge of the loop and as the load on the pump is increased 15 the higher the water rises in this side of the loop. At low loads the height of water on this side of the loop is not great and the excess work performed by the first stage wheel is destroyed by free falling and splashing of the water over the 20 top of the loop.

The device is shown as in actual operation as connected to hotwell H of the condenser C. These last elements are of the conventional type and no claim is made as to their novelty in this 25 application. Their illustration in the accompanying drawing serves to illustrate the principles of the invention. As clearly shown, a vac-

uum connection 85 leads from the top of the loop 53 to the outlet of the condenser C to equalize the vacuum in the loop and at the outlet to the condenser and to further aid the loop in performing its normal function of maintaining a full head on the first stage wheel. It will be clear to those skilled in the art that siphonic action in the loop may be avoided by carrying the pipe 53 more than 32 feet above the outlet of the lower stage impeller.

80

85

I claim:

A multiple stage pumping system for evacuating a variable pressure fluid supply including a two stage centrifugal pump adapted to be connected to the hotwell of a condenser and having a pair of impellers within a casing, each impeller operating to receive fluid from a fluid inlet and to discharge the same with increased head through a fluid outlet and means comprising a loop connecting the first stage fluid outlet and the second stage fluid inlet and extending above the pump for maintaining constant fluid potential on the first stage impeller, and means for maintaining substantial equal vacuum pressure in the loop and at the outlet to the condenser.
